GARMENT

Barbara V. Gould, Cleveland Heights, Ohio

Application February 12, 1949, Serial No. 76,083

5 Claims. (Cl. 2-27)

1

This invention relates to an improvement in girdles, and, more particularly, to a garment which may be worn as a girdle or may be simply and quickly converted to a panty-girdle.

Heretofore, girdles which may be converted to panty-girdles have accomplished this object by means of detachable crotch pieces which have been uncomfortable to wear due to the tendency of the garment to ride up. It is an object of my invention to provide a garment which, when worn as a girdle, provides excellent control of the lower abdomen and buttocks without being cut so low as to cut or be uncomfortable. At the same time, the girdle resists tendencies to ride up when worn. It is a still further object of my invention to provide means whereby the aforesaid girdle may be converted to a panty-girdle having no crotch piece, but rather, by pieces which, without pressure on the groin, restrain the garment from riding up and simultaneously control the upper thigh. It is a particular advantage of my invention that the above objects are achieved, even while the wearer may be engaged in active exercise or sports.

It is a still further object and advantage of my garment that a relatively small stock of the girdles and leg pieces may be employed to provide a wide variety of sizes.

In general, I achieve the foregoing objects and advantages by providing a girdle which is essentially comprised of two substantially independent bands of wide webs of elastic fabric, the two bands being interfitted and set at angles to each other so that the center of each band is above one hip and below the opposite hip of the wearer. The portion of each band which is worn below the point of the hip is preferably joined with a slide fastener which permits a somewhat narrower leg piece web to be joined to the band.

Although difficult to illustrate in two-dimensional drawings, the construction of my garment is actually relatively simple, as, along with other objects and advantages, will be apparent from the following specification, claims, and drawings, in which,

Fig. 1 is an elevation of my garment, pressed flat, when the garment is to be worn as a simple girdle.

Fig. 2 is an elevation of one of the pairs of leg pieces with which the girdle shown in Fig. 1 may be converted to a panty-girdle.

Fig. 3 is an isometric view of my garment when converted to a panty-girdle, the dotted lines indicating the relative position of one loop and attached leg piece.

2

Referring to Fig. 1 of the drawings in which the girdle per se is shown, the preferred embodiment of my girdle is comprised essentially of two substantially independent loops, or bands, 10 and 11, of elastic fabric, netting or webbing, which may either stretch along the run of the goods or may be so-called "two-way" stretch material. As shown in Fig. 1, ends of the material in the band 10 are joined together by the seam 12, which also joins the band 10 to the band 11 where the seam 12 overlies the band 11. Likewise, the ends of the band 11 are effectively joined together and to the band 10 by the seam 13, although the two bands 10 and 11 are also joined together adjacent the seam 13 by seam 14, the seams 13 and 14 defining the gusset 15 which carries the slide or other detachable fastener 16. The slide fastener 16, when open, permits the garment to be put on easily and, when closed, causes the upper portion of the garment to fit closely on the wearer.

It will be noted in Fig. 1 of the drawings that the portion of the band 11 immediately below the seam 12 is slit transversely, the edges of the slit 20 being joined by two slide fastener chain tapes 21 and 22 having an opening bottom stop and connected or disconnected by a slider 23. A similar slit 30 is provided in the portion of the band 10 immediately below the seam 13, said slit being opened or closed by means of the slide fastener chain tapes 31 and 32 and the slider 33. The chain tapes 31 and 32 are likewise provided with conventional opening bottom stops. Operation of the sliders 23 and 33 to open the slits 20 and 30 permit the girdle to be taken off or put on easily, but the principal purpose of the said slide fastener is to permit the attachment of the leg pieces in converting the girdle to a panty-girdle, as will be described below.

Except for the loose connection provided by the tabs 40 and 41 at the points of convergence of the tops of the bands 10 and 11 and the connection provided by the seams 12, 13 and 14, the two interfitted bands are substantially independent of each other. It is to be understood that where the edges of one band overlie the other band, such edges of one band may be tacked to the other band to prevent the bands from gapping with respect to each other; such tacking does not prevent the unstitched areas from moving with respect to each other nor substantially impair the function of the bands in sustaining the strains imposed thereon as though the bands were wholly independent of each other.

55 By being set at an angle to each other, as shown

in Fig. 1, each band acts, in effect, as a sling supported on one hip and confining and restraining the opposite buttock. At the same time, the crossed bands reinforce each other to support and restrain the lower abdomen of the wearer. Because the crossed bands are effectively independent of each other and can have at least limited movement with respect to each other in the areas where they are crossed, the garment restrains and confines the covered areas of the body of the wearer while effecting a minimum of restraint on the movements of the wearer. The garment may thus be worn without appreciable interference during active exercise.

It will also be noted that the angularity at which the two bands 10 and 11 are interfitted and set with respect to each other provides a garment conforming to the natural conformation of the hips and waist of the wearer. Further, the portions of the bands 10 and 11 worn above the pelvis run in a direction approximating the direction of the external and internal oblique muscles of the abdomen; simultaneously, the crossed portions of the bands which extend below the top of the pelvis and across the abdomen exert a confining and uplifting action on the whole lower abdomen. The garment tends to fit snugly above and below the hips of the wearer, while being cut high at the groin. The bottom edge of the garment does not tend to cut into the thighs of the wearer or produce a "girdle line" evident through outer clothing.

To convert the above-described girdle to a panty-girdle, a pair of leg pieces 50, one of which is shown in Fig. 2, are employed. The width of the leg pieces are equal to the length of the slits 20 and 30 and the lengths vary according to the size required for the wearer. The ends of the leg pieces 50 carry a pair of slide fastener chain tapes 51 and 52 having conventional opening bottom stops, a slider 53 being carried by the chain tape 51.

To attach a leg piece 50 to the band 11, the slit 20 is opened by sliding down the slider 23 and separating the chains 21 and 22. Then, by connecting the chain 52 to the chain 21 by the pulling up of the slider 23 and connecting the chain 51 to the chain 22 by pulling up the slider 23, the leg piece 50 becomes, in effect, a reversing spiral extension of the band 11 which encircles the thigh of the wearer, as indicated in dotted lines in Fig. 3 of the drawings. Because the slit 20 is cut transversely to the web 11 and the chains 51 and 52 likewise extend transversely to the leg piece 50, the leg piece 50 wraps around the thigh of the wearer at the same angularity as the band 11 extends across the abdomen and back of the wearer and thus encircles the thigh below the crotch.

To complete the conversion of the girdle shown in Fig. 1 to the panty-girdle shown in Fig. 3, a leg piece 50' is attached to the band 10 by means of the slide fastener at the slit 30 in a manner similar to that of attaching the leg piece 50 to the band 11. The arrangement of the leg piece 50' with respect to the band 10 is shown in Fig. 3 only to the extent that solid lines will permit, in order to minimize the confusion of a dotted line.

When my garment is worn as a panty-girdle, the discomfort of a crotch piece is avoided. At the same time, the leg pieces anchor the girdle bands securely because construction permits the leg pieces to wrap flat around the thighs of the wearer while following the natural conformation

of the body of the wearer and permitting relatively unrestrained hip movement.

In addition to permitting the garment to be worn either as a girdle or a panty-girdle, the detachable leg pieces also greatly simplify the corsetier's problem of stocking the garments to provide the variety of sizes required. Girdles are conventionally stocked in small, medium and large sizes; by stocking leg pieces in small, medium and large lengths, the garments may be fitted to nearly all customers, despite the characteristic lack of uniformity between the hip and waist sizes and upper thigh sizes of the customers. By utilizing the available permutations of girdle and leg band sizes, three sizes of each will provide nine size combinations for the panty-girdle.

While the preferred detachable fastening means employed in my garment are slide fasteners, it is to be understood that equivalent means, such as hooks and eyes, laces, and the like may be employed. Further, it is also to be understood that the bands and leg pieces need not consist of elastic material only, but may be made up of combined elastic and inelastic sections. This invention, therefore, is not restricted to the preferred embodiment disclosed but may be varied and modified within the scope of the following claims without departing from the spirit and purpose of my invention.

What is claimed is:

1. A figure-controlling garment comprising a first strip of relatively wide elastic material, a first seam joining the ends of said strip to form a first band, a second strip of relatively wide elastic material of dimensions substantially equal to said first strip, a second seam joining the ends of said second strip to form a second band, said first band being interfitted in said second band so that said bands cross at the front and back of said garment and overlap at the sides of said garment, and side seams at each side of said garment joining said bands at the overlapped portions, whereby said bands are capable of at least limited relative movement with respect to each other at the front and back of the garment where the bands cross.

2. The garment as defined in claim 1 in which said side seams also constitute part of the first and second seams joining the strips of elastic material forming the first and second bands at the over-lapped portion of said bands.

3. The garment as defined in claim 1 in which each of said bands is slit at the side of the garment where the band is the lower of the overlapped bands and detachable fastener elements on the edges of said slits and joining the edges of said slits when the garment is worn as a girdle.

4. A garment as defined in claim 3 including a first strip of relatively narrow material, and detachable fastener elements on the ends of each of said strips, the detachable fastener element on one end of one strip being joined to one edge of the slit in the first band and the detachable fastener elements on the other end of said strip being joined to the other edge of said slit to provide a thigh-encircling piece for the first band, and second strip of relatively narrow material similarly joined to said second band to provide a thigh-encircling piece for said second band when said garment is worn as a panty-girdle.

5. A panty-girdle comprising a first strip of relatively wide elastic material joined at its ends to form a waist-and hip-encircling portion of a

first band, an extension of relatively narrow material, integral with one end of said first strip and reversely spiraled and joined to the other end of said first strip to provide a thigh-encircling portion of said first band, a second band similar to first band, the waist and hip-encircling portions of said first and second bands being interfitted and set angularly with respect to each other so that a lower edge of the first band overlaps the upper edge of the second band above the thigh-encircling extension of the second band and the lower edge of the second band overlaps the upper edge of the first band above the thigh-encircling extension of the first band, and means joining said bands at their overlapped portions but otherwise permitting at least limited movement of the bands with respect to each other.
